UNITED STATES PATENT OFFICE.

PHILIP P. MELANSON, OF MONCTON, NEW BRUNSWICK, CANADA.

ROOF-BRACKET.

1,306,434.

Specification of Letters Patent. Patented June 10, 1919.

Application filed December 7, 1918. Serial No. 265,792.

To all whom it may concern:

Be it known that I, PHILIP P. MELANSON, a subject of the King of England, residing at Moncton, in the Province of New Brunswick and Dominion of Canada, have invented a new and useful Roof-Bracket, of which the following is a specification.

The device forming the subject matter of this application is adapted to be used on a 10 slanting roof, for the purpose of holding a paint bucket, tools or the like, or to serve as a platform on which a workman may stand.

The invention aims to provide a strong but simple roof bracket, which will have a 15 secure hold on a slanting roof, the construction being such that the bracket may be adjusted to correspond with the pitch of the roof. A further object of the invention is to provide a roof bracket which, although affording adequate support for a paint bucket or other object, will, at the same time, inflict 20 practically no injury on the roof.

It is within the province of the disclosure to improve generally and to enhance the 25 utility of devices of that type to which the present invention appertains.

Within the scope of what is claimed, a mechanic may make changes, without departing from the spirit of the invention, and as 30 to such details as may fall within the skill of a mechanic, I do not bind myself to the specific form shown in the drawings.

In the drawings:—Figure 1 shows in perspective, a roof bracket constructed in accordance with the invention, in place on a roof; Fig. 2 is a side elevation; Fig. 3 is a front elevation wherein parts appear in section; Fig. 4 is a top plan; Fig. 5 is a perspective disclosing the braces and the rod 40 which carries them.

The roof bracket claimed may be made of metal throughout, if desired, and includes base bars 1 provided at their inner ends with depending pointed prongs 2. Legs 3 extend 45 transversely of the base bars 1 and are located at the outer ends thereof, the legs being pointed as shown at 4, at their lower extremities. Supporting bars 5 are located between the base bars 1, spacing tubes 6 being placed between the bars 5, and between those bars and the base bars 1. A securing device, which may be a bolt 8, passes through the forward line of spacing tubes 6 and through the supporting bars 5. The bolt 8

is adapted to be mounted in any of a series 55 of openings 9, located in the legs 3, and spaced from each other, longitudinally of the legs. Braces 10 connected by a rod 25 are provided, the braces having angular ends 11 and 12. The ends 12 of the braces 10 are 60 pivoted in the legs 3 near to the lower ends thereof, and are equipped with heads 14 which prevent the lower ends 12 of the braces from becoming detached from the legs 3. The upper ends 11 of the braces 10 are 65 adapted to be received in any of a series of openings 15 formed in the base bars 1, and spaced longitudinally thereof. Nuts 16 are threaded on the ends 11 of the braces 10 to hold the braces assembled with the base 70 bars 1.

It will be clear from Fig. 1 that the prongs 2 of the base bars 1, and the pointed ends 4 of the legs 3, engaging the roof, will hold the bracket securely in place against slipping 75 downwardly along the roof. Preferably, the supporting bars 5 are not supplied with such parts as the prongs 2, and, therefore, there will be but few marks or indentations in the roof, and the roof will not be injured. Since 80 the bolt 8 may be mounted in any of the openings 9 in the legs 3, the bracket may be adjusted to correspond with the pitch of the roof, the upper ends 11 of the braces 10 being inserted into the proper openings 15 of 85 the base bars 1, and being held therein by the nuts 16. The supporting bars 5 are adapted to carry a paint pot or other object used by a mechanic. The tubes 6 not only hold the bars 5 spaced, but, as well, add to 90 the strength of the roof bracket.

I claim:—

1. A roof bracket comprising base bars provided at their inner ends with depending prongs; supporting bars between the base 95 bars; legs disposed transversely of the outer ends of the base bars and pointed at their lower ends; spacers between the bars at the forward and rear ends thereof; front and rear securing devices passing through the spacers and the bars; means for connecting the front securing device with the legs at adjusted points longitudinally of the legs; braces having their lower ends pivoted to the legs; and means for connecting the upper 100 ends of the braces with the base bars at adjusted points longitudinally of the base bars. 105
2. A roof bracket comprising base bars;

legs disposed transversely of the base bars adjacent to the outer ends thereof; a rod mounted to rock in the legs and comprising rearwardly extended braces engaging the inner surfaces of the legs to prevent the legs from moving toward each other, the rod having heads engaging the outer surfaces of the

legs to prevent the legs from moving apart; and means for connecting the rear ends of the braces with the base bars at adjusted points longitudinally of the base bars. 10

In testimony that I claim the foregoing as my own, I have hereto affixed my signature.

PHILIP P. MELANSON.
